UNITED STATES PATENT OFFICE.

VILHELM PAPE, OF CHARLOTTENBURG, GERMANY, ASSIGNOR TO GENERAL ELECTRIC COMPANY, A CORPORATION OF NEW YORK.

ELASTIC-FLUID TURBINE.

1,156,547.

Specification of Letters Patent. Patented Oct. 12, 1915.

Application filed April 3, 1915. Serial No. 19,044.

To all whom it may concern:

Be it known that I, WILHELM PAPE, a subject of the German Emperor, residing at Charlottenburg, Germany, have invented 5 certain new and useful Improvements in Elastic-Fluid Turbines, of which the following is a specification.

The present invention relates to elastic- 10 fluid turbine installation comprising a main turbine running condensing and an auxiliary running non-condensing and exhausting into an intermediate stage of the main machine. In connection with such installation there is danger that at very light loads 15 or no load on the main turbine the supply of exhaust elastic-fluid from the auxiliary turbine may be sufficient to cause the main machine to race, which, as is well known, is highly objectionable and may result in seri- 20 ous damage.

The object of the present invention is to provide an improved arrangement for regulating and controlling an installation of this character which will materially increase 25 the reliability of operation.

For a consideration of what I believe to be novel and my invention, attention is directed to the accompanying description and the claims appended thereto.

30 In carrying out my invention I place the supply of high pressure elastic fluid to the main turbine under the control of a speed governor driven by the main turbine. I then place the supply of elastic fluid to the auxiliary turbine under the control of a speed governor driven by the auxiliary turbine and also under the control of a speed governor driven by the main machine. This latter governor may be the same one which 35 controls the supply of elastic fluid to the main turbine, or it may be a separate one, and it may operate on the same valve mechanism as does the auxiliary turbine speed governor, or on an independent mechanism. 40 I prefer to use only a single speed governor on the main turbine and have it operate a valve mechanism which controls the supply of elastic fluid to both turbines, as this arrangement embodies several advantages as 45 50 will be pointed out hereinafter.

In the drawings, Figure 1 is a diagrammatic view, partly in section, of an installation embodying my invention; Fig. 2 is a

section on a larger scale of a hydraulic motor, and Fig. 3 is a detail view showing a 55 modification.

Referring to the drawing, 4 indicates the main turbine receiving elastic fluid through supply conduit 5 which may lead from any suitable source, and exhausting through conduit 6 to the condenser 7.

8 is an atmospheric relief valve which opens in case the condenser loses its vacuum.

9 indicates an auxiliary turbine. In the present instance it is shown as being used 65 to drive the circulating pump 10 and the wet air pump 11. The pump 10 supplies cooling water for the condenser through the pipe 12 and the pump 11 removes the condensation therefrom through pipe 13. The auxiliary 70 turbine receives elastic fluid through pipe 14 and has its exhaust pipe 15 connected to an intermediate stage or region of the main turbine. Pipe 14 is in substance a branch of the supply conduit 5. The passage of elastic 75 fluid from conduit 5 to the main turbine and to pipe 14 is under the control of the valve mechanism 16. In the present instance it comprises a motive fluid chest 17 from which leads a series of passages 18 to 80 the turbine nozzles or other fluid discharging devices. These passages are controlled by separately acting valves 19.

20 is a valve stem extending loosely through the valves and having a series of 85 abutments 21 thereon which are adapted to successively engage the valves 19 to uncover the passages 18. Fixed on the lower end of the stem 20 is a valve 22 which controls the passage of elastic fluid through pipe 14 to 90 the auxiliary turbine. The upper end of stem 20 is connected to the piston 23 of a hydraulic motor 24.

25 is the pilot valve having the usual valve bodies 26, admission pipe 27, and discharge 95 pipes 28. The stem 29 of the pilot valve is connected to the floating lever 30 which in turn is connected at one end to the speed governor 31 and at the other to the stem 20, thus forming a usual type of follow-up device. The operation of this type of valve gear is well known and needs no description. The pilot valve is provided with a sliding sleeve 32 (Fig. 2) which may be raised and lowered by the ordinary nut and screw operated by the hand wheel 33. By moving

this sleeve down as far as it will go the hydraulic motor will operate to completely close the valve mechanism 16. By this means it can be closed when the turbine is not running.

5 In the elastic fluid supply conduit 5 is a combined throttle and emergency cut-off valve 34. It may be of any approved type. It is arranged to be opened and closed manually by the hand wheel 35, and to be automatically tripped and closed by the speed governor 31 in case of excess speed of the main turbine.

10 The supply of elastic fluid to the auxiliary turbine is also controlled by the valve 36 operated by the speed governor 37 which is driven by the auxiliary turbine shaft. The valve 36 may also be controlled manually by hand wheel 38.

15 20 The operation is as follows: Assuming the installation to be idle and it is desired to start the same up, the hand wheel 33 on the main turbine is screwed down so as to completely close the valve mechanism 16. This 25 shuts off the supply of motive fluid to the main turbine and also to the pipe 14. The valve 36 is opened and is set to respond to the speed governor 37. The valve 34 is then opened admitting motive fluid to the chest 30 17. Since the valve mechanism 16 is closed, however, no motive fluid can pass to either turbine. The hand wheel 33 is now screwed up slowly. This will cause the hydraulic motor 24 to operate valve mechanism 16. 35 The valve body 22 will first be raised to admit motive fluid through pipe 14 to the auxiliary turbine 9. The auxiliary turbine will then start up in the usual way exhausting through the pipe 15 to the turbine 4. 40 At this time there will be no vacuum in condenser 7 and the atmospheric relief valve 8 will be open. There will, therefore, be no drop in pressure across the low pressure end of the main turbine and the exhaust from 45 turbine 9 will not tend to operate the same. The operation of the auxiliary turbine 9 puts the pumps 10 and 11 into operation to start the condenser 7. As soon as a suitable vacuum is reached in condenser 7 the 50 relief valve 8 is closed. In the present instance this relief valve is shown as being automatic, but it may be a simple hand valve. After the auxiliary apparatus is in operation the hand wheel 33 is screwed up 55 still farther raising the valves 19 and putting the main turbine into operation. The hand wheel is then screwed up as far as it will go. The speed governor 31 then assumes control of the main turbine and the 60 installation will operate in the usual manner. The auxiliary machine will be regulated by its speed governor 37. If, now, due to light load on the turbine 4, the exhaust from the auxiliary turbine 9 is sufficient to cause it to race, the speed governor 65

70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

31 will operate first to close off the admission of high pressure elastic fluid to the main turbine and then to throttle by means of valve 22 the passage of elastic fluid to the pipe 14. This will so limit the supply of motive fluid to the auxiliary turbine 9 that its exhaust will not be sufficient to cause the speed of the main machine to increase unduly. If, for any reason, as, for example by becoming dirty or covered with boiler scale, the valves 19 should fail to close completely so that there is more or less leakage to the main turbine 4 tending to cause it to race, the speed governor 31, upon the turbine reaching a predetermined maximum speed, will trip the emergency cut-off valve 34 and shut off the supply of motive fluid to both machines.

35 By the operation last described it will be noted that, when the emergency cut-off valve 34 is tripped, the supply of motive fluid to both the main turbine and the auxiliary turbine is interrupted. This causes a shutting down of the entire plant, which in some instances may be undesirable. In order to avoid this, the modification shown in Fig. 3 may be used. In this arrangement, 5^a indicates the main motive fluid supply conduit and 34^a the emergency cut-off valve. 17^a is the motive fluid chest of the valve mechanism corresponding to the valve mechanism 16 of Fig. 1, and 14^a is the pipe leading to the auxiliary machine. These parts may all be the same as in Fig. 1. The supply of motive fluid from the conduit 5^a to the pipe 14^a in the present instance is by way of the branch pipe 40 which shunts the emergency cut-off valve 34^a. This branch pipe is provided with a suitable hand valve 41. In accordance with this arrangement when the emergency shut-off valve 34^a is tripped the supply of motive fluid to the auxiliary turbine is not interrupted but will remain under the control of the speed governor 31 as before. The operation of the auxiliaries connected with the auxiliary turbine 9 will, therefore, not be interrupted or the condenser vacuum lost. With this arrangement the auxiliary turbine, therefore, is not shut down and in order to start the installation in operation again it is only necessary to reset the valve 34 and open the valve mechanism 16 by means of hand wheel 33, as described.

turbine. This may or may not be to the exclusion of governor 37, depending upon the relative speeds of the two machines.

By the present arrangement it will be seen that I have provided an installation wherein the possibility for the main machine racing is very remote and in which the installation is controlled in a very efficient manner.

10 In accordance with the provisions of the patent statutes, I have described the principle of operation of my invention, together with the apparatus which I now consider to represent the best embodiment thereof, 15 but I desire to have it understood that the apparatus shown is only illustrative, and that the invention can be carried out by other means.

What I claim as new and desire to secure 20 by Letters Patent of the United States, is,—

1. In combination, a main turbine, an auxiliary turbine exhausting into an intermediate stage of the main turbine, means responsive to the speed of the main turbine 25 for regulating the supply of elastic fluid thereto, and means responsive to both the speed of the main turbine and to the speed of the auxiliary turbine for regulating the supply of elastic fluid to the auxiliary turbine.

2. In combination, a main turbine, an auxiliary turbine exhausting into an intermediate stage thereof, a speed governor responsive to the speed of the main turbine, 35 valve mechanism operated thereby for controlling the admission of elastic fluid to both turbines, a speed governor responsive to the speed of the auxiliary machine, and valve mechanism operated thereby for controlling the admission of elastic fluid to the auxiliary machine.

3. In combination, a main turbine, an auxiliary turbine exhausting into an intermediate stage thereof, valve means controlling the admission of elastic fluid to the main turbine, valve means controlling the admission of elastic fluid to the auxiliary turbine, a speed governor responsive to the speed of the main turbine and connected to both said valve means and arranged to operate first the valve means of the auxiliary turbine and then that of the main machine,

a second valve means controlling the admission of elastic fluid to the auxiliary turbine, and a governor therefor responsive to 55 the speed of the auxiliary machine.

4. In combination, a main turbine, an auxiliary turbine having its exhaust connected to an intermediate stage thereof, and a governor responsive to the speed of the 60 main turbine for controlling the supply of elastic fluid to both turbines.

5. In combination, a main turbine, an auxiliary turbine having its exhaust connected to an intermediate stage thereof, a 65 governor responsive to the speed of the main turbine for controlling the supply of elastic fluid to both machines, and a governor responsive to the speed of the auxiliary turbine for controlling the supply of 70 elastic fluid to it alone.

6. In combination, a main turbine, an auxiliary turbine exhausting into an intermediate stage thereof, a speed governor responsive to the speed of the main turbine, 75 valve mechanism operated thereby for controlling the admission of elastic fluid to both turbines, a speed governor responsive to the speed of the auxiliary machine, valve mechanism operated thereby for controlling 80 the admission of elastic fluid to the auxiliary machine, a main conduit for supplying elastic fluid to said valve mechanisms, and an automatic cut-off valve in said main conduit which is closed when the speed of the 85 main turbine reaches a predetermined maximum value.

7. In combination, a main turbine, an auxiliary turbine having its exhaust connected to an intermediate stage thereof, a 90 valve mechanism for controlling the supply of motive fluid to both turbines, a hydraulic motor for operating it, a speed governor responsive to the speed of the main turbine controlling the hydraulic motor, and manually operated means for controlling the hydraulic motor to cause it to operate the valve mechanism.

In witness whereof, I have hereunto set my hand this fourth day of March, 1915. 100

WILHELM PAPE.
